BURNER

Nelson W. McLeod, St. Louis, Mo., assignor to
 Handlan-Buck Manufacturing Company, St.
 Louis, Mo., a corporation of Missouri

Application July 14, 1933, Serial No. 680,393

5 Claims. (Cl. 67—53)

This invention relates to a burner intended for use especially in railway hand lanterns which are subjected to severe motion in giving signals, and constitutes an improvement on the structures of United States Patents Nos. 1,276,417 and 1,879,329, granted respectively on August 20, 1918, and September 27, 1932, to George H. Rolfs and Louis C. Kuehner. The invention has for its object the production of a flame-spreading burner for a lantern of this kind which is so formed as to avoid extinction of the flame due to currents of air passing in close proximity to said flame. The flame spreader surrounds and surmounts the upper end of the wick tube, and includes provision therein for the entrance of air to supply oxygen to a flame burning from the wick, and said flame spreader also includes means for so protecting the air entranceways as to avoid movement of air there-through with sufficient force to interfere with the burning of the flame.

The improved flame spreader disclosed herein also is provided with apertures in the end walls thereof which are of such increased proportions that they serve the important function of supplying to the flame sufficient air to sustain the burning thereof, and thereby greatly reduce the likelihood that the flame will be extinguished in the ordinary use of the lantern. Furthermore, the body portion of the burner is provided with apertures formed in wall portions thereof which aid in supplying to the flame the oxygen necessary to sustain the flame, and in permitting air to pass downwardly into the oil font with which the burner is associated.

Fig. 1 is a plan view of the improved burner in position on a lantern font.

Fig. 2 is a side elevation of a fragment of a lantern font having the improved burner associated therewith, portions of the burner and a portion of the lantern font being shown in vertical section.

Fig. 3 is an elevation of the burner and a fragment of the font looking in the direction of the feathered arrow in Fig. 2, a portion of the burner being shown in section.

Fig. 4 is a horizontal section on line 4—4 of Fig. 2.

Fig. 5 is an inverted plan view of the improved burner.

In the drawing, wherein is shown for the purpose of illustration, merely, one embodiment of the invention, A designates a lantern font of any ordinary form, and B designates a burner fitted

to said font. The burner includes a wick tube b within which a wick C is arranged.

At the upper end of the wick tube of my burner a cup-shaped flame spreader D is arranged, this flame spreader comprising a bottom member 1 secured to the wick tube, end walls 2, and side walls 3, the side walls preferably being longer than the end walls, thereby rendering the cup-shaped spreader of elongated shape. In the side walls of the spreader are apertures 4, preferably of elongated shape, these apertures terminating in proximity to the top edges of said side walls and extending downwardly to points near the bottom of the spreader. The apertures 4 serve to admit air to the interior of the spreader D in a lateral direction through the side walls 3 to supply the necessary oxygen for support of combustion immediately above the wick of the burner, notwithstanding the fact that the wick terminates at the bottom of the spreader which extends thereabove.

The spreader D acts to spread the flame due to its extension above the height of the upper end of the burner wick, the flame being drawn to the walls 2 and 3 of the spreader, thereby enhancing the illuminating power of the flame above the spreader.

To avoid the direct passage of air currents through the apertures 4 with such force as might interfere with the steady burning of the flame within the flame spreader, I provide baffle wings 5. These baffle wings extend downwardly and outwardly from the top edges of the side walls 3 of the flame spreader, being inclined away from said side walls so that air may pass beneath them and then upwardly to enter the interior of the flame spreader through the apertures 4. The baffle wings flare outwardly from the top of the flame spreader, as described, and downwardly preferably to a horizontal line through the burner at a lower level than the bottoms of the apertures 4. Consequently there is no opportunity for strong currents of air to pass in a horizontal course through the apertures 4, but, on the contrary, all air entering the spreader through the apertures 4 must move in an upward course so as to pass beneath the baffle wings, and such air, by passing in an upward course, assists materially not only in supplying oxygen to the burner flame but also in maintaining a steady flame.

The baffle wings of my burner are preferably provided with apertures 5' so located as to permit the passage of a certain amount of air

through the baffle wings when a lantern equipped with my burner is lowered suddenly in giving signals. Therefore, when a lantern is so moved, there can be no sudden rush of air through 5 the apertures 4 in such quantity as to interfere with the proper burning of the flame within the flame spreader. As shown in Fig. 3, the apertures 5' are disposed in a lower horizontal plane than that in which the apertures 4 are 10 located. For the purpose of stabilizing the baffle wings so that they may not be bent from their proper inclined positions relative to the side walls of the flame spreader, I provide each baffle wing with a supporting leg 5^a suitably 15 secured at its lower end to the lower portion of the burner.

The structure which comprises the flame spreader D, baffle wings 5, and legs 5^a is preferably stamped from a single sheet of metal, 20 and this stamping is bent so as to produce a structure of the proper shape. The arrangement of the structure referred to is such that each baffle wing 5, at its opposite ends, is provided with inwardly extended flange portions 25 6, and at each end of the structure the inwardly extended flange portion 6 on the baffle wing at one side of the structure overlaps the inwardly extended flange portion 6 on the baffle wing at the opposite side of the structure, as shown at 30 the points designated by the reference character 7 in Fig. 1. Also, at the opposite ends of the bottom member 1 of the flame spreader D, said bottom member is provided with portions 8 which are bent upwardly and across the top 35 edges of the overlapping flange portions 6, and then downwardly in contact with the outer faces of the outermost flange portions. This arrangement provides the end walls 2 of the flame spreader, and as the portions 8 closely embrace 40 the overlapping, inwardly extended flange portions 6 of the wings 5, a very rigid structure is provided.

At opposite ends of the flame spreader the end walls 2 produced by the associated flange 45 portions 6 and portions 8 are notched, apertured, or otherwise cut away to provide openings 9. These openings are open at the top edges of the end walls 2 of the flame spreader and extend downwardly from said top edges, as 50 shown clearly in Figs. 2 and 3. The openings 9 are of substantially greater dimensions than are similar openings shown in the patent to Louis C. Kuehner, No. 1,879,329 previously referred to herein, and these openings of increased 55 proportions greatly increase the efficiency of the burner, inasmuch as the larger openings permit a greater amount of air to be delivered to the point of combustion of the flame so as to reduce to a minimum the likelihood of the flame being 60 accidentally extinguished.

The improved burner B disclosed herein includes a body portion B' which is in the form of an enclosed cylindrical chamber 10, as shown most clearly in Fig. 2, said chamber including 65 a bottom wall 10^a, an annular side wall 10^b provided with a shoulder 10^c, and a dome-shaped top wall 10^d which is secured in place by having its marginal edge portion crimped over an annular, horizontal flange 10^e located at the top of the side wall 10^b. The wick tube b of the burner 70 B is extended through the cylindrical chamber 10, said wick tube being passed through apertures in the top and bottom walls of said cylindrical chamber, and being suitably secured to

either or both of said walls. Extended transversely through the chamber 10 is a wick-adjusting element 11 which is rotatably supported in openings formed at diametrically opposed points of the side wall 10^b of said cylindrical chamber. The wick-adjusting element is provided with an operating member 12 at its outer end, and fixed to the portion of said wick-adjusting element located within the chamber 10 is a pair of toothed wheels 13. Portions of the 10 toothed wheels 13 are extended through slots 14 in the wall of the wick tube b and into said wick tube, as shown in Fig. 4, so that the teeth thereof bite into the wick C, and because of this arrangement the wick may be adjusted vertically 15 by rotating the wick-adjusting element 11. The slots formed in the wall of the wick tube are somewhat wider and longer than the portions of the toothed wheels which extend through said slots, for a purpose to be hereinafter set forth. 20

Formed through the top wall 10^d of the cylindrical chamber 10 is a plurality of apertures 15, and formed through the bottom wall 10^a of said cylindrical chamber is a plurality of apertures 16. The apertures 15 provide passageways 25 through which air may pass into the interior of the cylindrical chamber 10, and the apertures 16 provide passageways through which air may pass from the interior of the chamber 10 into the interior of the font A. In the operation of 30 the improved burner air passes through the apertures 15 downwardly into the chamber 10, and some of this air passes through the slots 14 in the wall of the wick tube and moves upwardly along the wick with the liquid fuel to the point 35 of combustion of the flame. Because of this arrangement an additional amount of oxygen is delivered to the point of combustion of the flame which aids in improving the quality and stability of the flame and reduces production of 40 smoke. Also, the presence of the apertures in the bottom wall of the cylindrical chamber 10 permits air to pass downwardly into the font A to replace fuel oil which is withdrawn therefrom by the burning of the flame. 45

I claim:

1. A burner of the character described, comprising a hollow body portion, a wick tube supported by said hollow body portion, a cup-shaped flame spreader secured to said wick tube, baffle wings flaring downwardly and outwardly from the upper portions of the side walls of said cup-shaped flame spreader, said hollow body portion having one or more apertures formed in a wall thereof through which air may pass into the interior of said hollow body portion, and wick-adjusting means having a portion extended through an opening formed in a wall portion of said wick tube which is located within said body portion, said opening in said wall portion of said wick tube providing a passageway for air which moves from the interior of said body portion into the interior of said wick tube and into contact with the wick therein. 55

2. A burner of the character described, comprising a hollow body portion, a wick tube supported by said hollow body portion, a cup-shaped flame spreader secured to said wick tube, baffle wings flaring downwardly and outwardly from the upper portions of the side walls of said cup-shaped flame spreader, said hollow body portion having one or more apertures formed in the top wall thereof through which air may pass into the interior of said hollow body portion, and wick-adjusting means having a portion extended 70

through an opening formed in a wall portion of said wick tube which is located within said body portion, said opening in said wall portion of said wick tube providing a passageway for air which moves from the interior of said body portion into the interior of said wick tube and into contact with the wick therein.

3. A burner of the character described, comprising a hollow body portion, a wick tube supported by said hollow body portion, a cup-shaped flame spreader secured to said wick tube, baffle wings flaring downwardly and outwardly from the upper portions of the side walls of said cup-shaped flame spreader, said hollow body portion having one or more apertures formed in the top wall thereof through which air may pass into the interior of said hollow body portion, and wick-adjusting means having a portion extended through an opening formed in a wall portion of said wick tube which is located within said body portion, said opening in said wall portion of said wick tube providing a passageway for air which moves from the interior of said body portion into the interior of said wick tube and into contact with the wick therein, the bottom wall of said hollow body portion being provided with an opening through which air may pass from the interior of said body portion into a fuel font with which the burner is associated.

4. A burner of the character described, comprising a hollow body portion, a wick tube supported by said hollow body portion, a cup-shaped flame spreader secured to said wick tube, said flame spreader having end walls provided with apertures, baffle wings flaring downwardly and outwardly from the upper portions of the side walls of said cup-shaped flame spreader, said hollow body portion having one or more apertures formed in the top wall thereof through

which air may pass into the interior of said hollow body portion, and wick-adjusting means having a portion extended through an opening formed in a wall portion of said wick tube which is located within said body portion, said opening in said wall portion of said wick tube providing a passageway for air which moves from the interior of said body portion into the interior of said wick tube and into contact with the wick therein, the bottom wall of said hollow body portion being provided with an opening through which air may pass from the interior of said body portion into a fuel font with which the burner is associated.

5. A burner of the character described, comprising a hollow body portion, a wick tube supported by said hollow body portion, a cup-shaped flame spreader secured to said wick tube, said flame spreader having end walls provided with apertures of increased dimensions, baffle wings flaring downwardly and outwardly from the upper portions of the side walls of said cup-shaped flame spreader, said hollow body portion having one or more apertures formed in the top wall thereof through which air may pass into the interior of said hollow body portion, and wick-adjusting means having a portion extended through an opening formed in a wall portion of said wick tube which is located within said body portion, said opening in said wall portion of said wick tube providing a passageway for air which moves from the interior of said body portion into the interior of said wick tube and into contact with the wick therein, the bottom wall of said hollow body portion being provided with an opening through which air may pass from the interior of said body portion into a fuel font with which the burner is associated.

NELSON W. MCLEOD.
